PRESSURE REGULATOR AND CUTOFF WITH
AUXILIARY MANUAL CONTROL

Erich Henkel, Calumet City, Ill., and Howard G. Nehrbas, Hammond, Ind., assignors to Combustion Engineering, Inc., a corporation of Delaware

Application December 27, 1948, Serial No. 67,426

4 Claims. (Cl. 50—4)

1

This invention relates to improvements in pressure reducing valves and to controlling means therefore comprising an under pressure valve to prevent steam from entering a steam line until a predetermined pressure has been reached in the steam generator and to prevent the steam pressure in the steam generator from falling below said predetermined pressure in case the steam demand on the generator is greater than its capacity.

When diesel-electric or other engines not having a native source of steam for heating a train are first coupled to a series of cold cars, the large and sudden demand required to initially heat the cars will more often than not overload the steam generator and cause a radical reduction in steam pressure. Similar reductions in steam pressure may occur when more cars are hooked into a train than it was intended that the generator on the engine should serve. A further source of loss of pressure in the steam train line and generator may occur from leaky couplings between cars. Reducing valves used to provide a lower steam pressure in the train heating line than exists in the generator contribute to these results because the greater the demand in the train line for whatever cause the more the valve will open to permit steam to flow from the generator so as to re-establish the desired heating pressure. All of these sources of excessive demand upon the generator are undesirable not only because they merely reduce the pressure in the generator and in the steam line but also since in so doing they may cause the small quantity of water in the generator to flash into steam with resulting danger of exposure of some of the heating elements to high temperatures in the furnace and gas passage.

Among the objects of this invention are an improved reducing valve under control of the pressure in the steam heat line on the downstream side thereof and operable when the differential pressure across it is at a minimum, which valve is an improved normally open type with provision for causing it to operate as a closed type reducing valve, and improved means for adjusting the same and for locking it in fully open position. A further object is an improved under pressure valve for closing said reducing valve until the pressure in the generator is initially brought up to a predetermined pressure and for releasing said reducing valve and controlling it to throttle the passage of steam to prevent the generator pressure from falling below a desired minimum and to prevent the generator from operating above its capacity, manual means for closing the reducing valve independently of the control by the

2

under-pressure valve, and the provision of various features of construction for insuring the proper operation of the system comprising the invention.

5 For the purpose of disclosure the invention will be described in its use in a steam heat line of a train shown in the accompanying drawings in which:

Figure 1 shows diagrammatically a train and 10 an arrangement of a system embodying the invention, and

Figure 2 shows in greater detail various parts 15 of the system in functional relation.

The invention is not limited to diesel or electric trains, or to trains of any description, but is applicable to stationary power plants as well. The steam generator on an engine is oil fired and is equipped with the usual operating and safety controls. The present invention has to do with preventing the flow of steam from the generator before the required operating pressure has been reached and with throttling the delivery of steam when required to maintain said pressure and to prevent the generator from exceeding its capacity.

20 In the diagrammatic showing in Figure 1 is disclosed a train consisting of an engine E and cars C. A steam generator SG is connected through a steam generator stop valve 5 to a pipe 6 connected to a reducing valve RV which controls the steam pressure in the train steam line 7. The pipe 6 is also connected by a pipe 8 to an under pressure valve UP that is provided to exercise certain controls on the reducing valve RV.

25 At AC is indicated the usual air compressor or reservoir connected to the train air pressure line and by a pipe 12 to the under-pressure valve UP and by a pipe 13 to the solenoid trip valve STV. Pipes 14 and 15 connect the valves UP and STV to the reducing valve RV to close the latter by air pressure under control of the former.

30 The pressure reducing valve RV (Fig. 2), located between the steam line 6 from the generator and the steam trainline 7, comprises an inverted T-shaped composite body provided with an axial passageway enlarged intermediate of its end to provide a valve chamber into which projects axially downstream an inlet member 16 provided with parallel upper and lower valve ports 17 with which cooperate movable valve elements 18 carried by a valve stem 19 extending through and guided in a web at the lower end of the upwardly extending projection 20 on the valve body. The latter is provided with a chamber 21 housing a steel bellows 22 bearing at its lower end against a shoulder on the valve stem and at

its upper end seated on a recessed shoulder in the upper end of the projection 20. The chamber 21 communicates with the valve chamber through ports in the web whereby said bellows will be subjected to the pressure of the steam in the valve chamber without being subjected to turbulence of the flow of steam. Threaded exteriorly on the upper end of the projection 20 and clamping the upper end of the bellows 22 against said projection is a cylindrical valve stem guide 23 provided with a vent 24 for the interior of the bellows. Guide 23 also has an upwardly opening air pressure cylinder 25 in which operates an air piston 26 surrounding said valve stem and bearing against a lower valve spring seat 27 secured to the upper end of the valve stem by a nut 28. The valve spring 29 is placed under compression by a follower 30 adjustable toward and away from the spring seat 27 by means of a rod 31 threaded in the upper end of a spring housing 32 threaded on the valve stem guide 23. The rod 31 may be provided with a hand wheel 33 and may be locked in positions of adjustment by means of a locking member 34.

Indicating means including a pointer 35 on the follower 30 projecting through a slot in the spring housing and a scale on the spring housing as indicated are provided as a gauge to facilitate the adjustment of the reducing valve spring to control the pressure of the steam delivered to the steam train line. The valve stem guide 23 is also provided with a passageway for conducting air under pressure from the pipes 14 and 15 into the air pressure cylinder 25 to close the reducing valve.

The reducing valve RV is mechanically constructed to be normally held open by the valve spring 29 but to be closed and held closed by air pressure until the desired steam pressure has been reached in the generator at which time the air pressure will be cut off automatically and the air cylinder allowed to bleed through bleeding ports, not shown, as is understood, to permit the reducing valve to open and operate under control of the valve spring 29 and the pressure of the steam at the downstream side of the valve.

In case of emergency the reducing valve may be opened and locked in open position by advancing the follower 30 to engage a projection 36 thereon with the nut 28 on the valve stem 19 as is obvious.

To close the reducing valve RV by admitting air pressure through the pipe 14 into the air pressure cylinder 25 an under pressure valve UP, Fig. 2, is provided to control the flow of air from the pipe 12 connected to the air compressor or reservoir to the pipe 14.

The underpressure valve UP comprises a base block 40 provided with a valve seat 41 connected by ports 42 and 43 to the pipes 12 and 14 suitably connected to the block. Cooperating with the valve seat is the conical valve face 44 of a rod-like floating valve member 45 adjustably carrying a spring follower 46 for placing a valve spring 47 under the proper initial compression to hold the valve open until the desired steam pressure has been attained in the steam generator. The upper end of the valve stem extends through an opening in a top plate 48 suitably supported on the base block 40 by sleeved rods 49 as shown. Mounted on the plate 48 is a steel bellows 50, the lower end of which is secured to the plate 48 by a bellows housing 51 connected by any suitable means to said plate to which the pipe 8 is connected to subject the bellows to generator steam

pressure. The upper closed end of the bellows comprises a bearing member 52 for the upper end of the floating valve member 45.

The construction of the under pressure valve UP is such that it will be held open by its valve spring to admit air pressure into the air pressure cylinder of the reducing valve RV until the desired steam pressure has been reached in the steam generator at which time the pressure on the bellows seats the under pressure valve 44 and shuts off the air pressure from the air pressure cylinder in the reducing valve and place the reducing valve under control of its spring and the pressure of the steam on the downstream side of the reducing valve.

In case of emergency, and normally when uncoupling the engine from the cars, it may be desirable to close the reducing valve at a time when the predetermined pressure in the steam generator has already been reached. For this purpose there is provided a solenoid trip valve STV, Fig. 2. This valve comprises a valve housing 60 ported as shown for establishing communication between the pipes 13 and 15 to bypass the underpressure valve UP when its movable valve element 61 is raised against its spring 62.

The valve element 61 is provided with a stem 63 projecting downwardly through the housing 60 for engagement by one end of a lever 65 pivoted on depending lugs 66 on a base 67 supporting said valve housing. The other end of the lever 65 is urged in a clockwise direction by a spring 68 interposed between said base and lever and surrounding a bolt 69 supported in said base to limit the clockwise movement of said lever. The lever 65 is normally held in the position shown by a known form of reset latch 70 cooperating with a lateral lug 71 on the lever. Operatively associated with said latch is the armature 72 of a solenoid 73 supported on said base and which may be energized by closing a switch 74 in the cab of the engine as is understood. When the solenoid is energized it trips the reset latch 70 whereupon the spring 68 will rock the lever clockwise and open the valve to by-pass the air pressure around the under pressure valve to close the reducing valve. The valve STV may be closed and the latch reset by manually rocking the lever 65 counterclockwise. This puts the reducing valve again under control of the under pressure valve.

To recapitulate: in operation the reducing valve functions to maintain in the train heating line a desired pressure lower than that existing at the generator. The under pressure valve by acting to close the reducing valve prevents the generator pressure falling below a predetermined value, say 200#, deemed essential to its proper and safe operation. Hence, neither hooking the engine to a cold train nor adding cars in excess of the capacity of the generator can result in lowering its pressure substantially below an optimum value. In addition, the uncoupling of an engine from the train is facilitated because the operator may without leaving his cab cut off the generator from the train line by operating the button energizing the trip valve.

What is claimed is:

1. The combination with a steam pressure line and an air pressure line, of a reducing valve in said steam pressure line, a valve spring normally holding said valve in open position, an air pressure cylinder operatively connected to said valve to move it into closed position, a normally open,

under-pressure air valve for admitting air into said air cylinder to close said reducing valve, and means subjected to the pressure of steam on the upstream side of said reducing valve and operable at a predetermined pressure to close said air valve and place the reducing valve under control of its spring and the steam pressure on the downstream side thereof.

2. The combination with a steam pressure line and an air pressure line, of a reducing valve in said steam pressure line, a valve spring normally holding said valve in open position, an air pressure cylinder operatively connected to said valve to move it into closed position, a normally open, under-pressure air valve for admitting air into said air cylinder to close said reducing valve, means subjected to the pressure of steam on the upstream side of said reducing valve and operable at a predetermined pressure to close said air valve and place the reducing valve under control of its spring and the steam pressure on the downstream side thereof, and control means connected in parallel with said air valve for admitting air into said air cylinder to close said reducing valve.

3. The combination with a steam pressure line and an air pressure line, of a reducing valve in said steam pressure line, a valve spring normally holding said valve in open position, an air pressure cylinder operatively connected to said valve to move it into closed position, a normally open, under-pressure air valve for admitting air into said air cylinder to close said reducing valve, means subjected to the pressure of steam on the upstream side of said reducing valve and operable at a predetermined pressure to close said air valve and place the reducing valve under control of its spring and the steam pressure on the

downstream side thereof, control means connected in parallel with said air valve for admitting air into said air cylinder to close said reducing valve, said latter means comprising a normally closed air valve, spring pressure means for opening said air valve, a manually resettable latch for holding said spring pressed means inoperative, and a solenoid for tripping said latch and releasing said spring pressed means to open said air valve.

4. A normally open under pressure valve for connecting a source of air pressure to a reducing valve in a steam pressure line for closing said reducing valve comprising: a valve seat, a movable valve element cooperating with said valve seat, and means controlled by a predetermined pressure of steam on the upstream side of said reducing valve for moving said movable valve element into closed position, said under pressure valve including means for moving its movable valve element away from its seat when said steam pressure falls below said predetermined value.
